Primary Examiner — Amy C Wierenga
Assistant Examiner — Jennylou M Binas

(57) CLAIM

The ornamental design for a makeup brush cleansing pad, as shown and described.

DESCRIPTION

FIG. 1 is a perspective view of a makeup brush cleansing pad showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 1. The broken lines in the drawings depict portions of the makeup brush cleansing pad that form no part of the claimed design. The dot dash broken line in FIGS. 1, 9 and 10 indicates cutoff boundaries for enlarged detailed portion views and form no part of the claim.

1 Claim, 10 Drawing Sheets
